DESIGN FOR A FIRE-PLACE LINING.

Design No. 12,279, dated May 24, 1881.

UNITED STATES PATENT OFFICE.

JOSEPH A. READ, OF PHILADELPHIA, PA., ASSIGNOR TO GILBERT COMBS
AND JOHN BAWDEN, BOTH OF FREEHOLD, N. J.

DESIGN FOR A FIRE-PLACE LINING.

SPECIFICATION forming part of Design No. 12,279, dated May 24, 1881.

Application filed April 22, 1881. Term of patent 7 years.

To all whom it may concern:

Be it known that I, JOSEPH A. READ, a citizen of the United States, residing in Philadelphia, Pennsylvania, have invented a new and original Design for a Fire-Place Lining, of which the following is a specification.

My design for a fire-place lining is shown in the accompanying photographic illustration.

The lining comprises a back plate, A, and opposite side plates, B B, the ornamentation of all of these plates being similar in character, and consisting, essentially, of panels *a*, containing, in relief, representations of birds perched upon twigs, the birds varying in character, and some being shown with folded wings and others with extended wings. The panels are separated by ornamentation *b*, of a character too fully shown in the drawing to need any detailed description.

I claim—

1. The within-described design for a fire-place lining, saiddesign comprising, essentially, panels ornamented with representations of birds in relief, as shown and described. 20
2. The design comprising the panels *a*, ornamented with representations of birds, and the intervening ornamentation *b*, as shown and described. 25

In testimony whereof I have signed my name to this specification in the presence of two subscribing witnesses. 30

JOSEPH A. READ.
